US00D985575S

(12) **United States Design Patent** (10) **Patent No.:** **US D985,575 S**
(45) **Date of Patent:** **** May 9, 2023**

(54) **DISPLAY STAND**

(71) Applicant: **NINGBO TUOTUO RIVER DESIGN COMPANY**, Zhejiang (CN)

(72) Inventor: **Xiaodong You**, Ningbo (CN)

(73) Assignee: **NINGBO TUOTUO RIVER DESIGN COMPANY**, Ningbo (CN)

(**) Term: **15 Years**

(21) Appl. No.: **29/752,885**

(22) Filed: **Sep. 29, 2020**

(51) **LOC (14) Cl.** **14-02**

(52) **U.S. Cl.**

USPC **D14/451**

(58) **Field of Classification Search**

USPC ..... D14/239, 371, 136, 375, 376, 451, 238; D8/363, 373, 394, 379, 380; D3/218; D6/672, 343, 681, 681.1, 681.2, 681.3 CPC .. F16M 11/04; F16M 2200/027; F16M 11/16; F16M 11/10
